UNITED STATES PATENT OFFICE.

PATRICK H. REARDON, OF SAN FRANCISCO, CALIFORNIA.

PRESSURE-REGULATOR.

No. 831,522.

Specification of Letters Patent.

Patented Sept. 18, 1906.

Application filed July 5, 1904. Serial No. 215,445.

To all whom it may concern:

Be it known that I, PATRICK H. REARDON, a citizen of the United States, residing in the city and county of San Francisco and State of California, have invented certain new and useful Improvements in Pressure-Regulators; and I do hereby declare the following to be a full, clear, and exact description of the same.

This invention relates to pressure-regulators for air-compressors and the like.

It has for its object a simple, cheap, and efficient device for maintaining the pressure in the receiver of an air-compressor at a predetermined amount and that when the pressure in the receiver exceeds that desired the compressing of air will temporarily be suspended. In devices heretofore employed for this purpose difficulty has been experienced in that when the pressure of the receiver has fallen below the desired amount and the compressor resumes compressing air a sudden and harmful jar is experienced upon the whole device, and especially upon the motor. This is owing to the motor immediately encountering the full pressure or resistance of the receiver. This shock or jar is emphasized by the fact that in all this character of devices, termed in the trade "unloading" devices, the work of the motor during its unloading period is reduced to a minimum, with the consequence that power is supplied during this time only in proportion to the load. It thus comes about that when the work of compressing air starts in and the motor has to encounter its full load it is compelled to slow down, and not infrequently it is stopped by the great accession of work thrown upon it thus suddenly.

A further object of the invention is to provide in this type of apparatus such a construction as will avoid the difficulty described—that is to say, to provide an apparatus so arranged that the load will be picked up gradually.

These objects are accomplished by means of the devices illustrated in the accompanying drawing, which is a sectional elevation of the device shown in position attached to an air-compressor cylinder, which is partly in section to more clearly illustrate the invention.

Referring to the drawing, 1 is an air-compressor cylinder of ordinary form having a piston 2.

3 3 are air-outlet valves, one on either end of the cylinder. Each of these valves fits

snugly into a recess 4, which is provided with a suitable plug-cap 5. The plug 5 may be provided with a valve-seat 6, adapted to engage with the outer end of valve 3 to form a joint. 60 Into the plugs 5 are screwed small pipes 7 7', which unite at any suitable point and continue as a single pipe 7, which is extended to a casing 8 of a regulator-valve or controlling device. The controlling device consists of, 65 besides the casing, a snugly-fitted plug or plunger-valve 9, seated therein. In the casing is a passage-way 10, extending longitudinally thereof, which is provided with two openings 11 and 12, extending into the bore of the casing at separated points, as shown in the drawing. The plug or valve 9 is provided with two separated longitudinal passages 13 and 14. The latter opens at one of its ends to the atmosphere, as shown at 15, while its 70 other end opens laterally to the periphery of the plug. The passage 13 is substantially similar, except that its outer end opens into the closed end of the casing-bore.

16 is an air-discharge pipe connecting both 80 end outlets of cylinder 1 by a bifurcation and continuing to the receiver. In the pipe 16 is provided a suitable check-valve 17, located, preferably, at some distance from the cylinder. A small pipe 18, connecting the bore of 85 the regulator-valve, enters the discharge-pipe 16 at a point between the valve 17 and the receiver. The plug-valve 9 is provided with a loading device, shown in the present instance as a yoke 19, supplied with weights 90 20. The plug-valve 9 is loaded so as to be raised by the desired receiver-pressure.

When the device is in operation, the following conditions normally exist: From the pipe 16 receiver-pressure is conveyed through passage 13, passage 10, and pipes 7 and 7' to the outer ends of the valves 3. When the desired pressure in the receiver is exceeded, it overcomes the weight 20 and raises the plug-valve 9 till the transverse opening of passage 10 95 engages with the upper opening of passage 14, closing by the same movement the connection of passage 10 with the receiver. This liberates the pressure on the outer ends of valves 3, so that by the pressure in pipe 16 100 beneath the check-valve 17 each valve is forced outward against the seats 6. There is thus provided a free passage from one side of piston 2 to the other around the bifurcation of pipe 16, so that all work of compressing 105 ceases, and the pressure of the receiver is on both sides of the piston. As the valve 17

prevents any accession of pressure from the receiver back to the cylinder, the pressure in the cylinder quickly diminishes, owing to unavoidable leaks around the piston-rod and elsewhere, so that in one or two strokes there is practically no pressure in the pipe 16 between the check-valve 17 and the cylinder. When the pressure in the receiver falls sufficiently to permit the plug 9 to drop to the position shown in the drawing, the valves 3 resume their normal working position and compressing commences, but not against the pressure of the receiver. Several strokes of the compressor-piston are necessary to fill the bifurcation of pipe 16 with air at receiver-pressure. Thus the engine or other motor has several turns in which to gradually take up the load, which it consequently does without shock or jar.

It is obvious that many changes both in the form and location of this device can be made to suit special requirements without departing from the essential character of my invention. I therefore do not desire to be confined to the particular form, location, or arrangements of the parts herein illustrated.

What I claim is—

1. A pressure-regulator for air-compressors and the like comprising an outlet-valve to the compressor-cylinder, a controlling device operated by pressure from the receiver to control the movement of said valve and a discharge-pipe from the cylinder to the receiver provided with a check-valve.
2. A pressure-regulator for reciprocating-piston air-compressors and the like comprising outlet-valves to the compressor-cylinder on each side of the piston, a controlling device operated by pressure from the receiver

to control the movement of said valves and a discharge-pipe from the cylinder to the receiver provided with a check-valve.

3. A pressure-regulator for reciprocating-piston air-compressors and the like comprising outlet-valves to the compressor-cylinder on each side of the piston, a bifurcated discharge-pipe connecting both ends of the cylinder at the outlet-valves with the receiver, a controlling device operated by pressure from the receiver to control the movement of the outlet-valves, the discharge-pipe being provided with a check-valve between the bifurcation and the receiver.

4. A pressure-regulator for reciprocating-piston air-compressors and the like comprising outlet-valves to the compressor-cylinder on each side of the piston, a bifurcated discharge-pipe connecting both ends of the cylinder at the outlet-valves with the receiver, a controlling device operated by pressure from the receiver to control the movement of said valves, said controlling device comprising a valve movable by the pressure in the receiver and means for controlling the movement thereof, pipes or passages connecting said outlet-valves with the receiver and with the atmosphere, suitably arranged whereby through the movement of the valve of the controlling device, receiver and atmospheric pressure are conducted to the outlet-valve whereby the movement of the last-mentioned valve is controlled and a check-valve in the discharge-pipe intermediate of the bifurcation and the receiver.
